HOWARD A. McCLELLAND, OF ALLENSWORTH, CALIFORNIA, ASSIGNOR OF THREE-FOURTHS TO H. H. TUCKER, OF LOS ANGELES, CALIFORNIA.

CONCENTRATING-TABLE.

1,186,811.

Specification of Letters Patent. Patented June 13, 1916.

Application filed September 28, 1915. Serial No. 53,042.

To all whom it may concern:

Be it known that I, HOWARD A. McCLELLAND, a citizen of the United States, residing at Allensworth, in the county of Tulare and State of California, have invented new and useful Improvements in Concentrating Tables, of which the following is a specification.

This invention relates to a concentrating table.

One of the objects of the present invention, is to provide a simple, compact, cheaply manufactured, easily operated and adjusted concentrating table, which is constructed to secure the concentrating effect of a vanning and flowing stream, and the stratifying and feeding action of reciprocal, vibratory or differential shake movement.

Another object of the invention is to provide means for deflecting the gangue matter passing over the table and simultaneously converging or gathering the separated material to enrich or thicken same at a plurality of points along the flow surface of the table, to permit a continuous and complete removal of same.

Further objects will hereinafter appear.

The invention consists of the parts and the construction and combination of parts as hereinafter more fully described and claimed, having reference to the accompanying drawings, in which—

Figure 1 is a plan view of the table proper. Fig. 2 is a side elevation of same, showing the application of one form of mechanism for imparting a reciprocal, vibratory, movement. Fig. 3 is an enlarged detail section on line 3—3, Fig. 1. Fig. 4 is a cross section on line 4—4, Fig. 1.

Referring to the drawings in detail, A indicates the table proper, which is constructed of wood, metal or any other suitable material and faced with a linoleum cover. The table shown in the present instance, is of the two-trough sluice box construction and each side is similar to the other. The construction of one side will hereinafter be described.

Arranged centrally between the side flanges 2 of the table, at a suitable distance from the pulp or feed box 3, is an auxiliary water supplying casing 4, to which water is delivered from a pipe 5, mounted on the lower side of the table, and connected with

a suitable source of supply, not here shown, the volume of water admitted being controlled by a valve 6. Formed on the forward end of the casing 4, is an elongated, flat discharge nozzle 7 and mounted interior of said nozzle is a skimmer plate 8, which is adapted to be adjusted vertically, by means of the screws indicated at 9. This skimmer plate is horizontally disposed and forms a cover for a discharge opening 10, in the table, which is provided for the purpose of permitting a continuous discharge of concentrates.

The table proper is mounted upon spring legs 11, and a reciprocal, vibratory movement is imparted to the table through a five-point toggle, generally indicated at 12, which is similar in construction to that used upon well-known Wilfley tables. This particular mechanism does not, however, form any important part of the present invention, and may, therefore, be varied or changed to suit conditions. Mounted on the table surface, is a pair of gathering boards 13 and 14; these boards are triangular in shape when looked upon from a plan view, and are disposed, one on each side of the nozzle. The sides of each gathering board are vertical, as indicated at 15, while the top faces are inclined outwardly as indicated at 16. The purpose of this construction will hereinafter be described.

The gathering boards are rather long and their inner walls present converging faces which are provided for the purpose of converging or gathering the concentrates and directing same directly into the mouth of the discharge nozzle.

In operation, as previously described, a reciprocal, vibratory action is imparted to the table, by means of the mechanism, generally indicated at 12. With this in operation, and pulp supplied by the feed box 3 and with the table inclined from the feed to the discharge end, it will be seen that the pulp will travel over the table surface in the direction of the arrow a. The pulp will in this manner, be subjected to the concentrating effect of a vanning and flowing stream and also to the stratifying and feeding action of reciprocal, vibratory movement. The pulp, consisting of finely crushed metaliferous ores or sands, together with the right proportion of water deposited upon

the table surfaces from the feed box 3, is immediately subjected to the concentrating and stratifying action described. The heavier particles or what are commonly termed concentrates, subject to this action will gradually settle on the table surface, as the pulp is flowing and moving in the direction of the arrow and the concentrates proper will gradually thicken and converge 5 toward the center line of the table, by means of the inclined or angularly disposed, vertical sides 15 of the gathering boards. The concentrates will in this manner be conveyed directly to the mouth of the nozzle, 10 where the gangue is deflected or thrown back by the outwardly flowing current of water supplied by pipe 5, and regulated by valve 6. This outward discharge of water however, only effects the gangue as the skimmer 15 plate 7 covers and protects the thickened layer of concentrates against the action of the water. The concentrates will thus be permitted to pass under the skimmer plate, where they are finally discharged through 20 the opening 10 by a receiving launder, not here shown.

The differential shaking action imparted to the table, together with the outwardly inclined faces 16 formed on the gathering boards imparts a lateral wave or vanning movement to the water and the pulp disposed between the gathering boards and this vanning movement, not only permits a constant discharge and removal of the gangue 25 over the faces 16 on the gathering boards, as the pulp mass as a whole is converged by the vertical sides 15, but also produces sufficient agitation to permit the concentrates to separate and stratify by the vibratory 30 movement. The greater mass of pulp is sheared off or deflected by the gathering boards before the concentrates reach the mouth of the discharge nozzle and the pulp thus deflected, runs down the inclined face 35 of the gathering boards in the direction of arrows 6, from there they reach the concentrating surface of the table where they are again similarly treated between a pair of deflecting boards and a nozzle, such as 40 shown. Any concentrates lost or passing over the first set of the gathering boards, will thus be caught and discharged through a second nozzle, in this manner permitting a perfect precipitation and separation of 45 the values, before the pulp or gangue finally reaches the tail end of the table.

By the employment of the concentrating table, constructed as here shown, it is found that careful preliminary sorting or separating of the various particles of crushed or comminuted material into different grades or classes, in which each separate class shall be composed of particles as nearly practicably of the same relative size, is not necessary, in other words, the table will handle 50

any pulp, portions of which may pass through a twenty mesh screen, while other particles may be sufficiently fine to be classed as slimes or two hundred mesh. The several actions, such as is caused by vanning, 70 vibration, etc., permit perfect separation and participation of concentrates, whether coarse or fine, without sorting or previous separation.

The materials and finish of the several 75 parts of the device may be such as the judgment and experience of the manufacturer may dictate.

I wish it understood that various changes in form, proportions and minor details of 80 construction may be resorted to within the scope of the appended claims, and that I do not wish to limit myself to the specific design and construction here shown.

Having thus described my invention, 85 what I claim and desire to secure by Letters Patent is—

1. A concentrator comprising a horizontally disposed table, means for imparting a differential shake movement to the table, an auxiliary water supplying casing centrally disposed on the table, said casing having an elongated flat discharge nozzle formed thereon, a skimmer plate mounted in the nozzle and forming a cover for a concentrate discharge opening, and a pair of angularly disposed gathering members secured on the table, one in each side of the nozzle. 95

2. A concentrator comprising a horizontally disposed table, means for imparting a differential shake movement to the table, an auxiliary water supplying casing centrally disposed on the table, said casing having an elongated flat discharge nozzle 100 formed thereon, a skimmer plate mounted in the nozzle and forming a cover for a concentrate discharge opening, and a pair of angularly disposed gathering members secured on the table, one in each side of the nozzle, said gathering members having vertically disposed sides and outwardly inclined faces. 110

3. A concentrator comprising a horizontally disposed table, means for imparting a differential shake movement to the table, an auxiliary water supplying casing centrally disposed on the table, said casing having an elongated flat discharge nozzle 115 formed thereon, a skimmer plate mounted in the nozzle and forming a cover for a concentrate discharge opening, a pair of angularly disposed gathering members secured on the table, one on each side of the nozzle, and means for adjusting the skimmer plate 120 vertically.

4. A concentrator comprising a horizontally disposed table, means for imparting a differential shake movement to the table, an auxiliary water supplying casing cen- 125

trally disposed on the table, said casing having an elongated flat discharge nozzle formed thereon, a skimmer plate mounted in the nozzle and forming a cover for a concentrate discharge opening, a pair of angularly disposed gathering members secured on the table, one in each side of the nozzle, said gathering members having vertically disposed sides and outwardly inclined faces,
5 and means for adjusting the skimmer plate vertically.

In testimony whereof I have hereunto set my hand in the presence of two subscribing witnesses.

HOWARD A. McCLELLAND.
